A. BERTRAM

BRUSH FOR STREET CLEANING MACHINES

Filed May 23, 1922

INVENTOR
August Bertram
M. A. Grumann
ATTORNEY

UNITED STATES PATENT OFFICE.

AUGUST BERTRAM, OF BROOKLYN, NEW YORK.

BRUSH FOR STREET-CLEANING MACHINES.

Application filed May 23, 1922, Serial No. 563,065.

To all whom it may concern:

Be it known that I, AUGUST BERTRAM, a citizen of the United States of America, residing at Brooklyn, in the county of Kings and State of New York, have invented certain new and useful Improvements in Brushes for Street-Cleaning Machines, of which the following is a specification.

This invention relates to street sweeping machines and has for its object to provide brushes therefor with means which while the brushes revolve will produce strong air blasts having the effect to loosen particles of dirt and stir up the dust adhering to the ground and thus enable a perfect sweeping of the street and gutter.

With these and other objects in view my invention consists in the novel construction arrangement and combination of parts as will be hereinafter more fully described and defined in the appended claims.

Fig. 1 is an enlarged cross sectional view of a brush; Fig. 2 is an enlarged section on line 2—2 of Fig. 1; Fig. 3 is an enlarged longitudinal section on line 3—3 of Fig. 2 of the blast producing mechanism of a brush; and Fig. 4 is an enlarged sectional perspective view of movable bearing for the axle of a brush.

Referring to the drawings in detail, 61 denotes a brush constructed according to my invention and provided with a plurality of blast producing devices which during the rotation of the brush will produce strong air blasts which will have the effect of stirring up the dust or loosening particles strongly adhering to the ground thereby insuring an effective and thorough sweeping.

The brush is mounted on the axle 100 of the street sweeping machine of which it constitutes a part. The brush is composed of a sleeve 104 rotatable on the axle 100. The bristles are arranged in tufts 141 around the periphery of said sleeve with free spaces 141' between them. Secured to the sleeve 104 to project radially through each space are pins or arms 142 to the outer ends of which are secured bearings 143 in which is rotatively borne a spindle 144 extending longitudinally of and parallel to the spindle 100. The end of the spindle 144 that projects outwardly from the inner end of the brush or space 141' carries an eccentrically curved arm 145 extending toward the axis of the brush. Fixed to spindle 144 is also a longitudinally extending bar 155

to which is suitably secured a socket 156 made of sheet metal and in which is borne a member 157 of flexible material, as rubber or the like. The flexible member extends substantially throughout the entire length of the brush and is adapted to bear with its outer longitudinal edge on the ground. Fixed to the bearings 143 of the spindle 144 is a plate 160 from which is yieldingly suspended, as by a hinge 159 or the like, a frame 158 extending throughout the length of the flexible member 157 and having end flanges 158', said flexible member being adapted to normally engage said frame and lie close to the inner face thereof.

Carried by the pin 142 located near the inner end of the brush is a horizontal arm 147 which also projects outwardly from the space 141' and has fulcrumed thereon a bell crank 146. One arm of said bell crank carries a roller 148 adapted to snugly bear on the concaved inner face of the curved arm 145 and the other arm carries a roller 149 adapted during the rotation of the brush 80 to ride over a cam surface 150 formed on a stationary arm 151 and located in the path of said roller 149.

Each bell crank 146 is actuated by a spring 152' of which one end is secured to 85 a stationary arm 153 projecting from the arm 147 and the other to an arm 152 projecting from the spindle 144.

During each revolution of the brush each bell crank 146 will be once operated by the 90 cam surface 150 and cause the flexible surface 157 of each to swing rearwardly around the axis of the spindle 144, and on being released from the cam 150 to be instantaneously and vigorously thrust towards 95 the back or frame 158. As a result thereof the air confined between said flexible surface 157 and the frame 158 will be expelled creating a strong blast that will stir up the dust and dirt particles on the ground 100 so as to be swept away by the succeeding tuft of the brush.

The axle 100 for each front brush is supported in a bracket 101 by means of a vertically movable bearing bar 102 formed laterally with end flanges 102' movably engaging the bracket 101 (Fig. 4). Rotatively mounted on the axle 100 is also a sleeve 103 on which is fixed a sprocket wheel 99. The sleeve 104 of the brush is provided at 110 its inner end with tooth shaped projections 105 adapted to engage axial correspondingly

shaped recesses 106 formed in the sleeve 103, whereby rotary motion is transmitted to the brush from a driven shaft (not shown) through chain 97, sprocket wheel 99 and sleeve 103.

When used as a right side brush 61 the latter is adapted to be resiliently yielding in axial direction, in order that it may adapt itself to the curvature of the curb, 10 when the machine turns a corner and to enable the thorough sweeping of the gutter. This is accomplished by providing a spring coil 107 between a washer 108 fixed to the inner end of the sleeve 104 and a washer 15 103' fixed to the sleeve 103. At the outer end of the sleeve 104, I provide a disc 108, which serves to shield the bristles 141 of the brush against curbstones.

The operation of the machine will be 20 understood from the detailed description of the different mechanisms.

It is evident that the mechanisms may be variously modified without departing from the principle of my invention. I, 25 therefore, do not wish to restrict myself to the details described and shown.

What I claim is:—

1. In a street sweeping machine, a rotary brush, a stationary cam surface and blast 30 producing means between the tufts of said brush operated from said cam surface.

2. In a street sweeping machine, a rotary brush having its tufts of bristles radially spaced apart, a plurality of blast producing 35 members in the spaces between said tufts, actuating means projecting outwardly from said spaces and a stationary cam surface arranged in the path of said actuating means to successively operate said blast producing members during the rotation of said brush.

3. In a street sweeping machine, a rotary brush, and a plurality of blast producing 40 means therein, each comprising a rocking flexible surface, a rigid surface adjacent

thereto and means for causing said flexible surface to periodically swing away from said rigid surface and be subsequently thrust back expelling the air between itself and said rigid surface.

4. In a street sweeping machine, a rotary brush and a plurality of blast producing means therein, each comprising a rocking flexible surface, cam operated means for actuating the same and a rigid surface against which said flexible surface is adapted to be periodically thrust to create a blast of air.

5. In a street sweeping machine, a rotary brush and a plurality of radially arranged blast producing means therein, each comprising a rocking surface, a cam operated spring controlled actuating lever therefor and a rigid surface against which said rocking surface is adapted to be periodically thrust to create a blast of air.

6. In a street sweeping machine, a rotary brush and a plurality of radially arranged blast producing means therein, each comprising a rocking surface, a cam operated spring controlled lever therefor and a rearwardly tilting rigid surface against which said rocking surface is adapted to be periodically thrust to create a blast of air.

7. In a street sweeping machine, an axle, a rotary brush composed of a sleeve rotatable and axially displaceable on said axle, tufts arranged in radially extending spaced rows around the circumference of said sleeve and fixed thereto, blast producing means in the spaces between said rows of tufts, means for transmitting motion to said sleeve and resilient means between said means and said sleeve tending to hold it against axial displacement.

In testimony whereof I affix my signature in presence of two witnesses.

AUGUST BERTRAM
